Attorney

UNITED STATES PATENT OFFICE.

HARRY CAPPELLANTI, OF MORGANTOWN, WEST VIRGINIA, ASSIGNOR OF ONE-HALF
TO ALPHRED D. LAVINDER, OF MORGANTOWN, WEST VIRGINIA.

GAS-FLOW ALARM.

Application filed July 31, 1923. Serial No. 654,885.

To all whom it may concern:

Be it known that I, HARRY CAPPELLANTI, citizen of the United States, residing at Morgantown, in the county of Monongalia 5 and State of West Virginia, have invented certain new and useful Improvements in Gas-Flow Alarms, of which the following is a specification.

This invention relates to gas flow alarms 10 and has particular reference to the provision of a device for automatically notifying a consumer when the supply of gas is shut off.

It is well known that gas burners are 15 often left lighted in buildings, for illuminating or other purposes, and that for various reasons the flow or supply of gas is interrupted, or cut off. When the supply of gas is thus interrupted, the burners are automatically extinguished and when the supply 20 of gas is continued again, the same escapes through the burners into the building so as to result in a waste of gas, the occurrence of an objectionable odor therefrom and even 25 the endangering of the lives of the persons in the building.

It is accordingly an object of the present invention to immediately automatically notify the occupant of the dwelling when 30 this discontinuance of the supply of gas takes place so that the burners may be turned off before the supply of gas is again restored and so that the escape of gas through the burners will be prevented.

35 An object of this invention is to provide a device of this kind which embraces the desired qualities of simplicity and durability of construction as well as efficiency in operation.

40 Another object of the invention is to provide an alarm device which may be cheaply and easily installed without the requirement of special skill.

45 Other objects will appear as the nature of the invention is better understood and the same consists in the novel form, combination, and arrangement of parts, hereinafter more fully described, shown in the accompanying drawings, and claimed.

50 In the drawings, wherein like reference characters indicate corresponding parts throughout the several views:

Figure 1 is a vertical sectional view

through the alarm device and the connections thereto in a gas line.

55

Figure 2 is a fragmentary detail sectional view taken substantially on the line 2-2 of Figure 1.

Referring more in detail to the drawings, 60 5 indicates an ordinary gas supply pipe, through which the flow of gas is controlled by means of a valve 6. The outlet end of the pipe 5 is externally threaded and screwed within the branch 7 of the multiway fitting, which has a lateral branch 8 provided with 65 means generally indicated at 9 for connection with a burner.

As shown in Figure 1, the outlet end of the pipe 5 projects within the chamber of the fitting between the ports 7 and 8, and is open at both ends. A bell shaped piston 9 is slidably mounted in the outlet end of the pipe 5 and the latter is provided with a lateral port 10 adapted to be closed by the bell shaped piston 9 when the latter is in its normal lowered position which it assumes by gravity when there is no gas pressure in the supply pipe 5. Thus, when the gas pressure is cut off in the line 5, the piston 9 assumes a lowered position by gravity to close the port 10 and is adapted to be raised by such pressure within the pipe 5 when the same is resumed so as to uncover the port 10 and permit the free flow of gas through the fitting from the pipe 5 to the burner.

75

80 The multiway fitting also includes a port 11 which is opposed to the port 7 and onto which is threaded a casing 12 of the alarm mechanism per se. This port 11 is closed by means of a packing gland generally indicated at 13, so as to prevent entrance of the gas into the casing 12 and said casing 12 85 contains a spring escapement-controlled alarm mechanism adapted to be held against operation when the piston 9 is raised.

90

95 As shown the alarm mechanism embodies a spring 14 adapted to be wound by a suitable key 15 secured upon the winding shaft thereof exteriorly of and at one side of the casing 12, which spring is adapted to rotate a gear 16 which is operatively associated with an escapement wheel 17 through a reduction gearing generally indicated at 18. This escapement wheel 17 is associated with 100 an escapement lever 19 in a well known manner and the escapement lever carries a 105

fixed hammer 20, the free end of which is provided with a head 21 adapted to intermittently strike a resonant shell 22 that is secured in a slot provided in one side of the 6 casing 12 by means of a screw 23. A rod 24 is readily attached to the piston 9 and extends upwardly through the stuffing box 13 where its upper end is impinged against the under side of an arm 25 that is rigid with 10 the escapement lever 19. The rod 24 is of such length as to hold the escapement lever 19 against rocking movement so as to render the hammer 20 inoperative when the piston 9 is raised by the pressure of gas in the supply line 5. On the other hand, should the pressure in the supply line 5 be discontinued for any reason the piston 9 will be allowed 15 to lower by gravity for releasing the rod 24 from the arm 25 and thereby permitting the escapement lever 19 to vibrate under the actuating influence of the spring 14 and the gearing 18 together with the escapement wheel 17 so that the alarm will be sounded. In this manner, the occupant of a building 20 is immediately notified when the supply of gas is discontinued for any reason and is thereby informed that the burners in the building should be inspected and if any were lighted that they should be turned off. 25

When this is done, no gas will escape into the building upon a resumption of the supply of gas to the burner, the occurrence of which will cause the piston 9 to again rise for engaging the rod 24 with the lever 25 and preventing operation of the escapement lever 19 and the hammer 20 carried thereby. 30

Should the device become out of order or inoperative for any reason, the escapement lever 19 may be manually held against movement by means of a hand operated lever 26 that is pivoted in the casing 12 and has a finger pin 27 extending outwardly through a slot 28 provided in one end of the casing. This lever 26 may be tightly mounted upon 35 its pivot 29 so that when the lever is manually moved, the inner end of the same will

remain in position wherein the arm 25 is held for preventing rocking of the escapement lever 19.

As shown, the fitting to which the supply pipe 5 is connected of the four way type, and the remaining branch 30 thereof which is in alignment with the port 8 is provided with a suitable closure plug 21 which may be removed for facilitating cleaning or repairs. 55 Also, the means 9 for facilitating connection of the fitting with a burner is shown as provided with a control valve 32 and adapted for connection with the burner by means of a flexible piping. However, it is to be understood that the present invention may be installed at any point in the gas supply line behind burners of a building in case a plurality of burners are used. 60

From the foregoing description, it will be 65 seen that I have provided a very simple and durable form of alarm which will effectively serve to notify a person upon the occurrence of a discontinuance of gas supply.

Numerous advantages of the invention 70 will suggest themselves to those skilled in the art and it is to be noted that minor changes may be made without departing from the spirit and scope of the invention as claimed. 75

What I claim as new is:

A gas flow control mechanism comprising a body, a pipe entering the body and provided at its side with an opening which is spaced from the interior surface of the body, a bell-shaped piston slidably mounted in the pipe and arranged to move over the opening, the concavity of the piston being disposed in the line of direction of the flow of gas through the pipe, an escapement mechanism mounted upon the body, and a rod connected with the bell-shaped piston and having an end portion disposed in the path of movement of one of the movable elements of the escapement mechanism. 85 90

In testimony whereof I affix my signature.

HARRY CAPPELLANTI.
